UNITED STATES PATENT OFFICE.

GEORGE W. LYNN, OF DETROIT, MICHIGAN.

FLYING-MACHINE.

1,070,972.

Specification of Letters Patent. Patented Aug. 19, 1913.

Application filed May 10, 1911. Serial No. 626,156.

To all whom it may concern:

Be it known that I, GEORGE W. LYNN, a citizen of the United States, residing at Detroit, in the county of Wayne and State of Michigan, have invented new and useful Improvements in Flying-Machines, of which the following is a specification.

This invention relates to flying machines of the "heavier than air type", and consists in the novel construction, arrangement and combination of parts hereinafter more fully described and claimed, reference being had to the accompanying drawings, in which—

Figure 1 is a side view of a device embodying the invention. Fig. 2 is a detail of one of the lifters and its mountings. Fig. 3 is a detail view of the rear propellers and rudder and their mountings and control. Fig. 4 is a detail of the front propeller and its mountings and control. Fig. 5 is a detail of the operating levers and their mountings, and Fig. 6 is a detail of the power transmission control.

As shown in Fig. 1, A is the platform constructed of any desired material that will allow of its being light in weight but strong and rigid in structure, and built in any suitable manner but with its front portion a^1 given a parabolical curve upward to assist its dynamical reaction in impinging on the ocean of aerial gas through which it passes. Besides performing the function of a platform on which are properly positioned the operator, motive power, and superstructure, it performs the multiple function of assisting the lifters to raise the flying machine when desired, of sustaining the flying machine alone when desired, or of acting as a parachute when desired, all by means of the operations and parts hereinafter more fully described.

B denotes the lifters, preferably four in number as shown in the drawings.

C are the rear propellers, D the rear rudder, E the front propeller, F the lever controls, G the power transmission clutches.

As shown in Fig. 2, B are the lifters. Each lifter is composed of four sections or blades b^1 , b^2 , b^3 , and b^4 , which are respectively pivotally connected to the mounting or shaft H, which is hollow, and is supported in position by the pole brace h^4 . Friction is reduced against this pole brace by means of ball bearings h^5 . The pole brace is embedded in the platform A. Each section of the lifter is composed of any suitable

light but strong materials and is built in two parts b^5 and b^6 . The part b^5 is built so as to give a straight surface which is retained in this relation by means of bracing ribs b^7 . The part b^6 acts as a fence or curbing to the part b^5 and is built to symmetrically follow the edging of part b^5 and to depend therefrom about four or five inches as illustrated in the drawings. Each section b^1 , b^2 , b^3 and b^4 ends in a lug or pivot member b^8 which is seated in the lifter mounting or shaft H, preferably by means of a flange, which is rigid or properly fastened to the shaft H.

Flexibly fastened to the under surface of each part b^1 , b^2 , b^3 and b^4 near the middle and near one of its side edges, and about one-third of the distance between the outer edge and the pivot lug are two operating rods b^9 and b^{10} . The rod b^9 of each section is rigidly fastened to an integral sleeve h^1 mounted on the lifter shaft H, so arranged that it will depend at an angle of about 45°. The rods b^{10} are likewise fastened to a sleeve h^2 by means of flexible connections. Said sleeve h^2 is allowed to slide up or down along shaft H. This sleeve h^2 has connected to it an operating rod h^3 suitably directed from the operator's seat by means of right angle yokes h^4 . The operating rod h^3 has its sleeve connecting end arranged in the form of a Y yoke, through the ends of which are run fastening pins or pivot lugs h^5 . By this means a flexible connection is made which allows of the angle of incidence of each of the sections b^1 , b^2 , b^3 and b^4 of the lifters to be changed as is desired so as to perform the functions of a lifting propeller or helicopter, or to maintain a sustaining surface to assist the platform surface A in keeping the flying machine aloft or to act as a parachute to break the fall of a quick landing.

b'' are superposed bracing rods placed across the center of the upper surface of each section b' , b^2 , b^3 , b^4 .

Each of the rear propellers is mounted upon a horizontal shaft c^1 in the same manner and operating under the same principles as the lifters. Thus c^2 is the main section of each propeller blade, braced by ribs c^3 , while c^4 is the pendant section along the edge, which is formed at right angles to part c^2 .

c^5 are operating rods flexibly connected to the forward surface of the propeller and

rigidly connected to a sleeve c^7 which is part of or rigidly fastened to the shaft c^1 so positioned that the rod c^5 is at an angle of 45° to the forward surface of the propeller c . The operating rod c^6 is flexibly fastened to the forward surface of the propeller C and also flexibly fastened to a sleeve c^8 which is allowed to slide along shaft c^1 . Operating rods c^5 and c^6 are flexibly fastened to the forward surface of the propeller part c^2 about one-third of the distance from the edge, one near one side edge and the other rod near the middle. Running from proper control levers at the operator's seat to each of the sliding sleeves of the propeller c^8 are operating rods I which are suitably mounted for operative action, as shown and illustrated in the drawings. By means of this form of construction the angle of incidence of one or the other of the propellers C can be changed at will so that the flying machine can be directed to the right or left as desired. Or again the angle of incidence of both of the rear propellers C can be changed at the same instant as is desired, to either increase or lessen the speed of the flying machine. As shown in Fig. 3, the propellers C are held in proper working position by means of the yoke brace J and shaft sockets j^1 which are fastened to the yoke brace J by means of the neck j^2 . This yoke brace and these shaft sockets are made of any suitable material which is light and strong.

The rear rudder or pin D is rigidly fastened to a support d^1 in a vertical position as shown in Fig. 1. The support d^1 is braced into position by means of the braces d^2 . The rudder is covered with any desired make of light but strong fabric while the support d^1 and braces d^2 are made of wood or metal tubing as desired. The function of said rudder D is to keep the flying machine from skidding when making a turn.

The front propeller E is composed of four sections e^1 , e^2 , e^3 and e^4 , and each section is composed of two parts e^5 and e^6 , built, arranged and operated the same as are the corresponding parts in each of the lifters or the rear propellers, that is— e^5 is braced by ribs e^7 , pivoted by means of a lug or pivot tongue e^8 to its shaft e^9 and operated by means of operating rods e^{10} and e^{11} . Each of the rods e^{10} are flexibly connected to the inside surface of a section e^1 or e^2 or e^3 or e^4 and rigidly fastened to a sleeve e^{12} which is part of or rigidly fastened to the shaft e^9 . Likewise each of the operating rods e^{11} is flexibly connected to the inside surface of each of the propeller sections and flexibly connected to a sliding sleeve e^{13} which is allowed to slide along the shaft e^9 when operated upon by means of the fulcrum arms K . The operating rods e^{10} and e^{11} are positioned at each section e^1 or e^2 or e^3 or e^4 on the inside surface of the propeller, as stated heretofore,

about one third of the distance in from the outer edge, one rod near one side edge and the second rod near the middle. They run to the shaft e^9 at about an angle of 45° .

The flexible yoke K , including its members k^2 and k^3 , is so positioned that the angle of incidence of the sections e^1 , e^2 , e^3 , and e^4 can be changed at will through the medium of the operating rod L , the bell-crank l^1 and the balance rod l^2 , which run from the operator's seat to the said flexible yoke K . The balance rod l^2 is centrally pivoted at k^1 and supported by means of brace supports l^3 , the flexible yoke member k^2 is connected to a hinge joint of the flexible yoke K , while the outer joint of the flexible yoke member k^2 is pivotally hinged to the sliding sleeve e^{13} . The opposite flexible yoke member k^3 is flexibly fastened to a sleeve yoke k^4 which is rigidly fastened to a^1 in such a manner as to positively support the front propeller shaft e^9 .

The front propeller shaft e^9 is divided into two portions by means of the knuckle joint M . The forward portion of the shaft e^9 is slidably mounted on a half round table m^1 which is rigidly attached to the forward portion a^1 of the platform A . This allows of a right or left hand movement of the front propeller (operating means not shown).

Each respective operating rod on the flying machine has a corresponding operating lever at the operator's seat, said levers being positioned within handy reach. All of the levers are placed in a group and loosely mounted upon a rod N , by any old and well known means and are retained in operative position by means of quadrants or other suitable stays or racks n^1 . On each lever handle is fastened a pinion member of any old and accepted design which has a biting pinion n^2 designed to play along a ratchet toothed rack n^3 rigidly fastened to the retaining quadrant stay or rack n^1 . This allows each of the operating levers to be locked in any desired position.

The motor O transmits force by means of a main shaft o^1 to which is suitably geared by means of bevel gear wheels o^2 , each of the lifter shafts H . Force is transmitted to the two rear propellers C by means of standard chain and sprocket gearing P and p^1 fastened to the end of the main shaft o^1 . Clutches G in the vicinity of the motor O allow of a make and break arrangement to shut off or start the main shafts o^1 (operating means not shown).

The flying machine has the regular standard chassis wheel base.

The operation of the flying machine is as follows: The operator, starting his motor, adjusts the lever controlling the lifter sections so that the lifters operate under a high degree of incidence until the flying machine

has attained the desired altitude. Then changing the incidence of the lifters to zero so that they become in the nature of a continuous flat plane, the operator operates the lever controlling the incidence of the front propeller sections so that the sections are drawn to a steep angle of incidence, and thus a high forward speed is obtained. If a right or left turn is desired, the front propeller shaft is turned correspondingly, and the degree of incidence is changed on the proper rear propeller. If the carrying load is too great for the platform A to sustain alone, the propellers are given the proper degree of incidence to assist. If a landing is attempted, the descent is regulated by the degree of incidence of the lifters. If the flying machine is in operation and the motor should happen to stop, the lifters are brought into a plane and so act as parachutes to assist in breaking the fall. The rear propellers assist the front propellers in driving the flying machine forward according to the degree of incidence allowed, and the speed is regulated by the degree of the angle of incidence of all of the propellers.

As heretofore stated the platform A also is a sustaining surface, assisting the lifters B. Thus, every part of this form of flying machine is co-related and assists a corresponding part, and each one acts as a check on the others.

Having thus described the invention, what I claim as new, is:—

In combination with a flying machine, a propeller having adjustable controlled pitch blades, and means to control the pitch of said blades consisting of an operating rod, a bell-crank lever, a balance rod connected to said bell-crank lever and centrally pivoted on a brace support, and a connecting arm running from said balance rod to a pair of fulcrum arms, said fulcrum arms being connected to said propeller, as described and illustrated.

In testimony whereof I affix my signature in presence of two witnesses.

GEORGE W. LYNN.
